WALTER CLIFFORD, OF HOLLY SPRINGS, MISSISSIPPI.

Letters Patent No. 83,762, dated November 3, 1868.

IMPROVED MODE OF CARRYING KNAKSACKS.

The Schedule referred to in these Letters Patent and making part of the same.

To all whom it may concern:

Be it known that I, WALTER CLIFFORD, captain thirty-fourth United States infantry, stationed at Holly Springs, Mississippi, have invented a new and improved Method of Carrying the Knapsack now in use, or for carrying any weight to be borne on the shoulders or back; and I do hereby declare the following is a full and exact description thereof, reference being had to the accompanying drawings, and to the letters of reference marked thereon, in which—

Figure 1 represents the shoulder-springs, belt, and appurtenances;

Figure 2, the shoulder-springs without the belt; and Figures 3 and 4, the device as worn and used.

Similar letters of reference indicate corresponding parts.

The nature of my invention consists in two shoulder-springs, of metal or its equivalent, padded and covered with leather, and so formed as to fit over each shoulder down to the waist of the wearer. These springs are held in position by a waist-belt and suitable bands and thongs. To the top of the shoulder-springs is secured, by rivets or otherwise, one or more strong, light buckle-straps, to which the knapsack is strapped, so that the weight of the burden rests almost entirely upon the shoulders, and acts as a brace for them, and instead of making the wearer round-shouldered and flat-chested, as the modes of carrying knapsacks now in use do, it will have an effect entirely opposite, keep-

ing the carrier erect, and the chest thrown forward, allowing the lungs to have full play; and furthermore, the action of the arms are not impeded, and by bringing the cartridge-boxes on the belt to the front of the body, the weight of the knapsack will be so well balanced that the belt can be worn, when desired, unbuckled, without danger of the knapsack falling off.

In the accompanying drawings,

A A are the shoulder-springs, reaching from the waist-belt B, in front, up and over the shoulders, and down to the waist-belt behind.

a a are the buckle-straps, to which the knapsack is attached.

b b are slides placed on the waist-belt B, between the cartridge-boxes g g, to which the shoulder-springs are attached by means of the thongs d d. The shoulder-springs are held in position at the small of the back by the buckle-strap e, which can be lengthened or shortened to suit the wearer.

What I claim as my invention, and desire to secure by Letters Patent, is—

A device for carrying knapsacks, composed of the padded shoulder-springs A, back-brace e, belt B, slides b b, and thongs d d, when combined, constructed, and applied as herein shown and described.

WALTER CLIFFORD.
